METALLIC DOOR FRAME

Filed Oct. 10, 1927

Inventor
William J. Gross
By his Attorney
Merchant and Kilborn

UNITED STATES PATENT OFFICE

WILLIAM J. GROSS, OF ST. PAUL, MINNESOTA, ASSIGNOR TO GROSS METAL PRODUCTS COMPANY, OF ST. PAUL, MINNESOTA, A CORPORATION OF MINNESOTA

METALLIC DOOR FRAME

Application filed October 10, 1927. Serial No. 225,261.

My present invention has for its object the provision of an improved metallic door frame having detachable, endwise reversible and interchangeable jambs to permit a door to be 5 hung four different ways in the door frame so as to swing either in or out, or from the left or the right. These jambs are provided with two rabbeted door seats and double faced door stops therebetween. Hinged 10 seats are formed in one of the rabbeted door seats of one of the jambs, and by endwise reversing the respective jamb, the door may be hung to swing either in or out, or by interchanging the two door jambs, said door may 15 be hung to swing either from the right or the left.

To the above end, generally stated, the invention consists of the novel devices and combinations of devices hereinafter described 20 and defined in the claims.

In the accompanying drawings, which illustrate the invention, like characters indicate like parts throughout the several views.

Referring to the drawings:

25 Fig. 1 is a side elevation of the improved door frame and a door hung therein;

Fig. 2 is a fragmentary view in elevation showing the upper left-hand corner of the door frame with the door removed, on an 30 enlarged scale;

Fig. 3 is a view partly in transverse vertical section taken on the line 3—3 of Fig. 1, on an enlarged scale, and is also a face view of a portion of the door jamb having the 35 hinge seats formed therein;

Fig. 4 is a fragmentary view principally in section taken on the line 4—4 of Fig. 3, on an enlarged scale; and

Fig. 5 is a fragmentary detail view in section taken on the line 5—5 of Fig. 3.

The numeral 6 indicates a wall diagrammatically illustrated and having a door opening in which the improved door frame 7 is mounted and permanently secured by the 45 customary or any suitable means. This door frame 7 is channel-shaped in cross section, and door casings 8 are integrally formed with the side flanges thereof. The upright and horizontal members of the door frame 50 7 and door casings 8 are each formed from

a single sheet of metal, and the side flanges of said frame and the adjacent edge portions of said casings, which extend at right angles thereto, afford rabbeted seats 9 on each side of the door frame 7, for a purpose that will presently appear. 55

A header 10, channel-shaped in cross section, has its side flanges seated in the rabbeted seats 9, overlap the side flanges of the horizontal member of the door frame 7 and are 60 detachably secured thereto by screws 11. The header 10 is formed from a single sheet of metal and has two rabbeted door seats 12, and a double faced door stop 13 between said seats. 65

For each upright of the door frame 7 is a door jamb 14 that is channel-shaped in cross section with its side flanges extending into the rabbeted seats 9, overlap the upright side flanges of the door frame 7 and are detachably 70 secured thereto by screws 15. Each door jamb 14 is provided with two rabbeted door seats 16 of the same width as the door seats 12, and a double faced door stop 17 between said seats 16 of the same width as the door stop 13 (see Fig. 3). The door jambs 14 extend the full distance from the header 10 to the floor, and both ends of said header are notched to receive the end portions of the jambs 14, as best shown in Fig. 2, with the 75 so ends of the door stop 13 abutting the opposing faces of the door stops 17.

One of the jambs 14 is cut away to afford upper and lower hinge seats 18, and hinge-acting metallic straps 19 extend through the fields of said seats within the respective jamb, and their end portions are rigidly and permanently secured by spot welding to said jamb, both above and below the seats 18. The intermediate portions of the straps 19 are 85 inwardly offset to receive the respective members of a pair of hinges 20 so that their outer faces are flush with the outer face of the respective door seat 16. These straps 19 are drilled and tapped to receive screws 21 90 that detachably secure the hinges 20 to the respective door jamb 14.

A hollow metallic door 22, as shown of the slab type, is hung by the hinges 20 in the door frame 7. This door 22 is provided with hinge 100

seats and hinge straps 23, like the straps 19 to which the respective hinges 20 are secured by screws 24. It is important to note that the hinges 20 are located the same distances from either end of the respective jamb 14 and the door 22 so that said door 22 may be turned end for end and hung to swing either in or out. By removing the screws 15 of one of the door jambs 14, said door jamb 10 may be turned end for end to bring its hinge seats 18 on either side of the door stop 17 so that the door 22 may be swung either in or out, or by removing the screws 15 from both door jambs 14 said door jambs may be 15 interchanged and endwise positioned so that the door 22 may be hung to swing either from the left or the right as well as in or out.

As best shown in Fig. 4, the side flanges of the jambs 14, at their longitudinal edges, 20 engage perpendicular portions of the casings 8 at the rabbeted seats 19 and thereby rigidly hold the jambs 14 in position and at the same time make neat and finished joints between the door jambs and the casings 8.

25 What I claim is:

1. In an integral metallic door frame and casing, jamb members having two rabbeted door seats with double faced door stops therebetween, at least one of said jambs being 30 endwise reversible and detachably applied to continuous faces of the integral frame and casing.

2. A metallic door frame, the uprights of which are channel-shaped in cross section, 35 door casings integral with the side flanges of the frame, said frame having jambs that are channel-shaped in cross section with their side flanges overlapping the side flanges of the frame and engaging the adjacent edges 40 of the casings as stops, and exposed fastening means detachably securing the jambs to the frame, whereby said jambs may be removed from the frame without disturbing the casings.

45 3. A metallic door frame, the uprights of which are channel-shaped in cross section, door casings integral with the side flanges of the frame, said frame having jambs that are channel-shaped in cross section with their 50 side flanges overlapping the side flanges of the frame and engaging the adjacent edges of the casings as stops, and exposed fastening means detachably securing the flanges of the jambs to the flanges of the frame.

55 4. An integral metallic door frame and casing adapted for permanent attachment in a wall and permitting a door to be hung to either upright side of the frame and to swing either in or out therefrom after the frame is 60 installed and without altering the permanently fixed door frame, comprising in combination jamb members detachably secured to continuous faces of the integral frame and casing and each having registering 65 double faced door stops, and one of said jamb

members having hinge seats and being endwise reversible relative to the sides of said frame and casing.

5. In an integral metallic door frame and casing, reversible and interchangeable jamb members having means for detachably securing said jamb members to continuous faces of said frame and casing.

6. An integral metallic door frame and casing rabbeted adjacent opposite sides of 70 said frame to provide continuous faces, and reversible and interchangeable jamb members having side flanges detachably secured to said faces.

7. In an integral metallic door frame and casing, jamb members having laterally projecting side flanges overlapping continuous faces of the frame and casing, and exposed 75 fastening means detachably securing the flanges of the jamb members to said faces, whereby the said jamb members may be removed from and attached to the frame without disturbing the frame or casing.

In testimony whereof I affix my signature.

WILLIAM J. GROSS.
